UNITED STATES PATENT OFFICE.

CHARLES W. STARK, OF TRENTON, NEW JERSEY.

BUILDING STRUCTURE COMPRISING WATER RECEPTORS.

Application filed December 30, 1926. Serial No. 157,916.

In modern building practice it is customary to build bath tubs, or shower receptors into the wall. This is done by setting the preformed tub or other article against the 5 unfinished wall, and then applying cement against the wall which extends down against the upper surface of the tub. The wall is usually finished by applying tile or plaster outside of the cement. 10 The tub is relatively heavy, and as the building grows older the tub tends to settle. This is particularly true if a solid porcelain tub is used, but is also true where the tub is made of porcelain covered metal. This 15 settling is apt to leave a crack between the bottom of the tile or plaster at the top face of the tub, through which water may leak into the wall.

One of the difficulties to be met in overcoming this defect is the fact that it is 20 highly inadvisable to anchor the tub to the upper portion of the wall, for if this is done the weight of the tub will tend to crack the cement backing and displace the tiles.

I have discovered that a substantially 25 water-proof union can be made between the tub or other article and the wall, if such article, (which for convenience I call a water receptor, intending to embrace within this term both solid porcelain and enamel covered plumbing fixtures of various types adapted to receive water such as tubs, shower receptors, sinks and the like) is formed with a sheet of smooth metal extending upwardly 30 from the upper face of that portion of the receptor which is intended to be built into the wall. This metal should be firmly anchored into the receptor, but as stated, it should be smooth, and also should be flexible 35 where it extends above the face of the receptor. The metal plate should be so positioned that when the wall is finished it is embedded in the cement or plaster backing. Due to the fact that the metal is smooth 40 and flexible, it will not be anchored in the cement of the wall, so that if the tub settles it will move relatively to the cement, and thus will not drag the wall down with the settling tub. The amount of settling is 45 usually not much in excess of one-eighth ($\frac{1}{8}$) of an inch, and by having the metal plate extended as much as one-half ($\frac{1}{2}$) of an inch above the facing of the receptor, an ample engagement between the metal and 50 the cement will remain, so that the gap will

be dammed against the flow of water into the wall.

One of the principal reasons for making the metal flexible is the fact that in shipment the metal is very apt to become bent. 60 If stiff metal is used it is apt to be left with waves or rough spots when it is bent back into a vertical position by the plumber who is installing the article. This would tend to anchor the metal to the cement of the wall, 65 which as pointed out is highly inadvisable. If the metal is made of brass or other appropriate metal, it can be sufficiently flexible so that the entire plate may be bent down for shipment, and then can readily be 70 raised in position when the receptor is to be built into the wall.

The metal plate may be anchored into the ceramic body in any desired way, but in the accompanying drawing I show one method 75 in which this can be done. In the drawing Fig. 1 shows a cross-section of a portion of a wall into which a bath tub has been built; Fig. 2 shows the same parts after the tub has settled; and Fig. 3 shows a particular 80 form of metal plate.

The back edge of the tub which is designated by the numeral 2, is provided with a recess 4 which is restricted at the opening. A plate of brass 6 is bent into an angle and 85 inserted into a recess 4. The recess is then filled with cement 8, thus firmly anchoring plate 6 in place. The wall shown comprises the studding 10, metal lath 12, the scratch coat of plaster 14, and the cement bed 16, 90 which it will be noted surrounds the upper portion of the plate 6. The wall is provided with a finishing coat 18 which may be tile or plaster.

Fig. 2 shows the same parts as Fig. 1, but 95 after the tub has settled. It will be noted that the plate 6 is still firmly anchored in the recess 4, and has moved relative to the cement 16, but the upper edge of plate 6 still extends into the cement 16 and serves as a 100 dam for the water.

In Fig. 3, I show a method of cutting the metal strip 6', so that the strip can be bent to follow curves in the shape of the receptor.

What I claim is:

1. In a building construction a wall, a water receptor of the type described having a portion built into the wall, a recess with a restricted opening formed in the upper face of that portion of the receptor which 110

extends into the wall, a metal plate anchored by cement in said recess and extending upwardly therefrom, and cement, forming part of the wall, embracing the upper portion of said metal plate but not anchored thereto, whereby a joint is formed between the receptor and the wall which will provide a water stop both at the time when the receptor is built into the wall and after relative movement of the receptor and the wall has taken place.

2. A water receptor of the type described having a portion adapted to be built into a wall having a metal plate anchored in the

upper face of said portion, and extending 15 above the upper face of the receptor, said plate being smooth and flexible, whereby the same may be set in cement without being anchored therein to form a joint with such cement which will provide a water stop 20 despite relative movement of the receptor and such cement.

3. A structure as defined in claim 2 in which the metal plate is anchored by cement in a recess formed in the upper face of the 25 receptor.

CHARLES W. STARK.
